UNITED STATES PATENT OFFICE.

MINOR KENNER, OF NEW ORLEANS, LOUISIANA.

MOP-ASSEMBLING APPARATUS.

Application filed September 14, 1926. Serial No. 135,426.

This invention relates to mop assembling apparatus, an object of the invention being to provide improved means for assembling the strands of yarn wherein an internally 5 grooved segmental ring is employed over which the strands are run, and in said ring binding wire or strands are located and can be readily secured around the inner runs of the yarn. It is this construction and arrangement of ring and mounting therefor which facilitates the assembling of the mop and which constitutes the essential feature of my invention. By reason of the employment of this mechanism I am enabled to 15 quickly, conveniently and efficiently assemble the mop, which will be strong and durable in use.

With this and other objects in view, the invention consists in certain novel features 20 of construction and combinations and arrangements of parts, which will be more fully hereinafter described and pointed out in the claims.

In the accompanying drawings—

25 Figure 1 is a view in side elevation, showing my improved assembling apparatus in operative position;

Figure 2 is an enlarged fragmentary view, showing the assemblage of the mop with my 30 improved segmental ring;

Figure 3 is a view in transverse section on the line 3—3 of Figure 2;

Figure 4 is a view in longitudinal section on the line 4—4 of Figure 3;

35 Figure 5 is a view, partly in elevation and partly in section, showing the strands secured to the sliding sleeve;

Figure 6 is a view in section on the line 6—6 of Figure 5;

40 Figure 7 is a view in elevation of my improved completed mop;

Figure 8 is a plan view of my improved ring and its mounting;

Figure 9 is a view in section on the line 45 9—9 of Figure 8;

Figure 10 is a plan view, showing the ring support open for the removal of the ring;

Figure 11 is a perspective view of my improved ring.

50 Referring more particularly to Figure 1, 2, and 3 are uprights which are adapted to support a mop handle 4 in horizontal position for assemblage. On the upright 1 a clamping device 5 is provided for the reception of one end of the mop handle, and this device 5 has pins 6 thereon to receive the

runs of the mop yarn during assemblage. 7 represents a sliding sleeve on the mop handle 4, and 8 is my improved ring, and it is this ring and its mounting which constitute the essential feature or features of my invention, the other parts of the invention being more or less standardized and hence shall not be described in detail.

The ring 8 above referred to is not a complete ring but is formed with a gap so that the ring will be hereinafter referred to as segmental. This ring 8 is preferably of metal or other suitable material, is of appreciably greater diameter than the sleeve 7 70 and is of somewhat channel shape in cross section so as to provide an internal groove 9.

The ring 8 is fixed to an angle arm 10 and this angle arm 10 has a tongue 11 thereon which is adapted to fit in a recess 12 in a 75 supporting arm 13. This supporting arm is fixed to a block 14 at the upper end of upright 3 and has connected thereto a bar 15 which is pivotally connected to the block at one end, as shown at 16. This bar 15 carries a bolt 17 with a wing nut 18 thereon, and the arm 13 and tongue 11 are made with recesses 19 and 20, respectively, to permit the bolt 17 to enter said recesses, so that when the parts are assembled with the tongue 11 85 in recess 12 the nut 18 can be tightened and the parts will be assembled.

In normal operation, the ring 8 is located around one end of sleeve 7 and over an annular groove 21 in said sleeve, as clearly 90 shown in Figures 2 and 3. When the parts are in this position, the mop yarn 22 is run backwardly and forwardly longitudinally of the mop handle, the runs being positioned around the pins 6 and then under and over 95 the ring 8 backwardly and forwardly until a sufficient amount of yarn is assembled, the ends of the yarn being secured together in approved manner.

The gap in the ring 8 has three separate 100 and distinct functions: First, when the ring is in place it allows the yarn to be stretched freely and quickly put between pins 6 and the ring 8; second, the gap allows the ring to be quickly removed from the handle; and, 105 third, it allows the binding strand or strands to be inserted in the groove of the ring after the yarn has been assembled. Hence, after assembling the yarn on the ring, the next step is to insert the binding 110 strand or strands in the groove of the ring and secure them around the inner runs of

the yarn, clamping the latter in the groove 21 of sleeve 7.

Suitable tying strands 24 may be located intermediate the ends of the mop, as shown 5 in Figure 1, and various other devices may be employed, but as above stated the invention has particularly to do with the ring, its mounting and its operation.

After the wire 23 is secured, the ring must 10 of course be removed, and to do this the nut 18 is loosened, the bar 15 swung to one side, and the ring removed from the arm 13, as clearly indicated in Figures 10 and 11. The ring can then be manipulated off of the 15 sleeve 7 to the shank portion of handle 4 and can be manipulated on the shank so as to remove the same from the mop. Previous to this, however, the mop is tied around the handle by means of strands 25 20 so that when removed from the apparatus the mop is complete and the ring can be again positioned for assemblage of another mop.

Various changes and alterations might be 25 made in the general form of the parts described without departing from the invention, and hence I do not limit myself to the precise details set forth but consider myself at liberty to make such slight changes and 30 alterations as fairly fall within the spirit and scope of the appended claims.

I claim:

1. A mop assembling apparatus, including 35 an internally grooved segmental ring adapted to be positioned around a member and receive a tying strand therein, said ring adapted to receive the strands of the mop yarn over the same in the assemblage of the mop.

40 2. A mop assembling apparatus, including

an internally grooved segmental ring adapted to be positioned around a member and receive a tying strand therein, said ring adapted to receive the strands of the mop yarn over the same in the assemblage of the 45 mop, a support, and means removably connecting the ring to the support.

3. A mop assembling apparatus, including 50 an internally grooved segmental ring adapted to be positioned around a member and receive a tying strand therein, said ring adapted to receive the strands of the mop 55 yarn over the same in the assemblage of the mop, an arm on the ring, and clamping means having a fixed support adapted to receive and removably hold the arm.

4. A mop assembling apparatus, including 60 an internally grooved ring adapted to be positioned around a member and receive a tying strand therein, said ring adapted to receive the strands of the mop 65 yarn over the same in the assemblage of the mop, an arm on the ring, clamping means having a fixed support adapted to receive and removably hold the arm, said clamping means including a raised arm adapted to receive the first mentioned arm, a movable bar adapted to be positioned over said arm, a bolt carried by said bar, and a nut on said bolt adapted to clamp said bar and arms together.

5. In a mop assembling apparatus, the 70 combination with a support, and a segmental ring adapted to receive the runs of yarn thereover and support said runs in clamping 75 position around a member, said ring having an internal groove adapted to receive a tying strand.

MINOR KENNER.
